UNITED STATES PATENT OFFICE.

MARSHALL MILLER AND THOMAS S. LEAKE, OF CHICAGO, ILLINOIS.

AUTOMATIC COALING-STATION.

1,288,959.

Specification of Letters Patent. Patented Dec. 24, 1918.

Application filed April 27, 1914. Serial No. 834,796.

To all whom it may concern:

Be it known that we, MARSHALL MILLER, a citizen of the United States, residing at Chicago, in the county of Cook and State 5 of Illinois, and THOMAS S. LEAKE, a citizen of the United States, residing at Chicago, in the county of Cook and State of Illinois, have invented certain new and useful Im- 10 provements in Automatic Coaling-Stations, of which the following is a specification.

Our invention relates to coaling stations for locomotives, or the like, where it is desirable to elevate coal or other commodities to a position convenient for loading into 15 locomotive tenders or other cars or conveyances.

Our invention comprises a continuously rotating element to which are pivotally attached reciprocating elements which actuate the elevating buckets. We utilize the period of substantial rest at the extremities of the movements of the reciprocating elements for loading the buckets and discharging them. The said periods of substantial 25 rest occur at what are commonly known as the dead points where the reversal of movement of a reciprocating member occurs which is actuated by a rotating member.

We find that this mechanical principle is 30 exceptionally useful in the work to which we have applied it for numerous reasons, among which is the fact that the movement of the parts is entirely unaccompanied by shocks and severe stresses and strains com- 35 monly occurring in the starting and stopping of mechanisms of this class. Another fact in favor of this mechanism is that during the intermediate portion of the movement the speed may be quite high without 40 danger. The acceleration and retardation of the movements of the buckets are both gradual and unaccompanied by shock. Our mechanism for this reason is automatic as the buckets come to their starting and stop- 45 ping positions automatically without the at- tention of an operator.

Our invention has a very simple character and consists of a suitable motor, reducing 50 gearing for giving a relatively low rotative speed of the rotating element above mentioned, reciprocating elements pivotally attached to said rotating element, multiplying gear such as ordinary pulley blocks attached to said reciprocating members, and cables 55 leading to the buckets.

Other objects and advantages of our improved coaling station will be rendered apparent in the following specification, when taken in connection with the accompanying drawings and the novel elements and combinations thereof will be more particularly set forth in the claims. 60

In the drawings—

Figure 1 is an elevation of a coaling station with our improved elevating mecha- 65 nism applied thereto.

Fig. 2 is an elevation at right angles to the view shown in Fig. 1.

Fig. 3 is an elevation showing more in detail the essential parts of our improved 70 mechanism.

Fig. 4 is a detail of one of the crank arms attached to the rotating element.

Fig. 5 is an elevation of certain parts of our mechanism as viewed in a direction at 75 right angles to the view occurring in Fig. 3.

Fig. 6 is a sectional detail of the bucket loading mechanism.

Fig. 7 is a sectional view of the upper portion of said mechanism taken along the 80 line 7, 7 of Fig. 6.

Fig. 8 is an elevation of the bucket and a portion of said bucket loading mechanism.

Our invention comprises a heavy rotating gear wheel 15 to which are rigidly attached 85 the crank arms 16 and 17 oppositely disposed with relation to the axis of said gear wheel. Pivotally attached to the extremities of these crank arms are the reciprocating elements or connecting rods 18 and 19. 90 These rods carry at their upper ends the multiple sheaves 20 and 21 respectively which are in turn connected with sheaves 25 and 25^a attached to fixed portions 27 of the framework by suitable hangers 26. The 95 cables 22 and 23 pass successively around the sheaves of the pulley blocks in the customary manner and serve to greatly increase the movement produced by the connecting rods 18 and 19. 100

The cables extend from the said pulley blocks upwardly in the coaling station, as shown at 28 and 29, and pass over sheaves 30 and 31 in the upper part of the station and are led around over sheaves 33 and 34 105 and downwardly into the shafts or guideways in which the buckets travel as shown at 35 and 36. The said cables are finally attached to the buckets 37 and 38. In Fig. 2 one of the buckets is shown midway in 110

its vertical travel at 39 and the extreme upper and lower positions are shown in dotted lines.

The buckets discharge their contents into a bin 40 from which the coal is drawn off through a spout 41 to the locomotive tender on the track 42. The coal is received by the buckets from a hopper 43 beneath a track 44.

Referring more particularly to Fig. 6, the hopper 43 will be seen to open into a chute 45 leading to a gate 46 which in turn opens into a measuring chamber 47. A second gate 48 controls the movement of the coal from said measuring chamber into the bucket 38.

The gate 46 has a vertical movement and is actuated by levers 49 which are pivotally connected to said gate by the intermediate links 50. Said links provide for communicating the angular movement of said levers to the reciprocating movement of said gate. The gate is attached to a horizontal bar 51 and is guided by the angle pieces 52 secured to the side walls of the chamber. The upper portion of the gate is guided by the edges of the slot 46^a and the lower portion by said angle bars. The levers 49 are pivotally mounted on bearings 53.

The levers 49 of the gates, controlling the loading of one bucket, are connected to the corresponding levers controlling the gates leading to the other bucket by a cable 54 passing over sheaves 55 and 56 suitably supported upon the framework, as shown for instance in Figs. 1, 6 and 8. When the gate leading to one bucket is open the other one is closed.

The gate 48 is pivotally attached to the framework at 60 and is adapted to swing downwardly when discharging the contents of the chamber 47. The said gate is provided with side wings 59, which have a position outside of the side walls of the measuring chamber 47. The said wings are provided with weight members 58 for counterbalancing the weight of said gates 48. These weight members are so proportioned as to retain the gates in closed position due to their angular relation to them and to have little or no effect upon said gates when open. As seen in Fig. 6, the said weights 58 have a position directly above the pivotal point 60 when the gate is open wherein they have little or no effect upon the gate and the weight of the gate itself causes it to remain in an open position. When, however, the gate is closed the said weight 58 will have a position at one side of the pivot, while the gate itself would have a position above the pivot whereby the gate is quite securely held in its closed position.

The gate is moved to closed position by the upper edge 61 of the bucket when it rises. A rod 62 has a position below the weights 58 and is carried by arms 63 fixed

to a shaft 64 mounted upon the frame member 65. Other arms 66 fixed to said shaft are struck by the cam members 67 on the bucket and serve to elevate the shaft or bar 62, whereby the gate is tilted toward its open position, the weight of the coal and gate completing the opening movement.

A movable bar 68 is given a position in the path of the bucket below the same, said bar being guided in a vertical direction by guideways 68^a. This bar 68 is connected by means of tables 69 at its opposite ends to a bar 70 attached to the ends of the levers 49.

The cables 28 are attached at their extremities to the bucket carrying frames or cages 71 at the lower part of which are members 72 receiving the weight of the buckets. These members have guide lugs 73, which slide upon ribs or guideways 75 secured to the vertical timber 76 of the structure. In the bottom of the pit in the path of the buckets we interpose supporting blocks 77, which intercept the buckets a little before they have reached the lowermost position of the travel of the frames or cages 71. The movement of the said cages 71 below the stopping points of the buckets is that which takes place during the period in which the lower extremities of the connecting rods 18 and 19 are passing the dead centers in the rotary movement of the gear 15.

In the lower portion of the buckets we provide a guide pin 80 which is adapted to slide in the vertical guideways 81 secured to the member 72. The upper extremities of the said guideways are closed, as shown at 82^a, whereby the bucket is prevented from leaving the cage when discharging its contents into the bin at the upper extremity of its movement. A horizontal portion 83^a of the main bucket guide supports said bucket while in its discharging position. The rollers 84 carried by said bucket rest upon this portion of the guide when discharging. The upper guideway 83^a tilts the bucket.

The crank arms 16 and 17 are provided with adjustable blocks 86 which carry the pivot pin by which they are attached to the connecting rods 18 and 19. The blocks 86 are associated with other blocks 89 by which adjustments can be made, said blocks 89 being movable to positions either side of the block 86. Finer adjustments can be made by means of the set screws 88 which are locked in position by nuts 90. The outer portions of the crank arms are provided with rectangular openings 91 in which said blocks are fitted.

The heavy gear 15 is supported by a shaft 92 which is provided with bearings 95 secured to the under side of the horizontal frame members 94 which are rigidly con-

5 nected by means of the inclined compression members 96 with the sheave support members 27. The tension produced in the connecting members 18 and 19 is thereby 50 counteracted by the compression members 96.

10 The heavy gear 15 is driven by the pinion 98 fixed to the same shaft with a gear 97 which is in turn driven by a pinion 99 secured to a shaft upon which is also fixed a gear 100. The gear 100 is driven by pinion 101 which is fixed to a shaft upon which is also secured the driving pulley 102. A belt 103 leads from said pulley to a motor 104 in the power house 105.

15 In the operation of this mechanism it is necessary only to start the motor 104 when it proceeds automatically. The belt 103 and reducing gear described causes a slow rotation of the heavy gear 15, each semi-rotation 20 thereof producing a complete movement of the buckets between the bottoms of the pits and the tops of the coaling station. While one of the buckets is rising the other is descending due to the fact that the connecting 25 rods 18 and 19 are attached at opposite sides of said gear 15. During the period of rest at the bottom one of the buckets is receiving coal, while the other during a corresponding period of rest at the top is discharging its 30 contents into the bin 40. The periods of rest at the top and bottom of the movements is ample for the purpose, but at the bottom we have provided the supporting blocks 77 for the buckets which permit the supporting 35 member 72 to continue its movement downwardly to the turning point and to return and pick up the bucket while ascending. It will be observed that the movement of all the parts of the elevating mechanism is continuous, but that the motion is so extremely slow 40 at the turning points that there is ample time for the filling and discharge of the buckets.

45 The bucket in its downward movement strikes the bar 68 and through the mechanism previously described closes the gate 46 which prevents the movement of the coal into the measuring chamber 47, while the coal previously contained therein is discharging into the bucket 30. Simultaneously 50 with the closing of the gate 46, the levers 66 are operated by the bucket to rotate the gate 48 about the pivot 60, thereby permitting the coal in said chamber 47 to flow into the bucket.

55 The downward movement of said bucket causes the gate 46 in the other chute which opens into the second bucket to become opened by the cable 54 previously described. The chamber 47 corresponding to said second 60 chute will thereby be filled ready for discharge into the second bucket when it has reached the bottom of its movement. The operations in filling said second bucket proceed in the same manner as in the first.

65 It will be seen that we have produced a

mechanism which automatically and very smoothly and silently elevates the coal from a pit to the bin with greater speed than the mechanisms now commonly used in which the buckets are started and stopped suddenly 70 and which move at a uniform rate between the top and the bottom. With our mechanism the speed throughout the intermediate portion of the movement may be quite high without dangerous or injurious effects and 75 the total time consumed in elevating by our mechanism will be much less than that heretofore attained. While the speed in the intermediate portion of the movement may be quite high, that at the ends may be very 80 slow, and the gradual acceleration and retardation of the movement may take place with no shocks or severe stresses and strains. It will be observed that there is no clutch mechanism in our device and that all of the 85 results are attained with simple and positively operating structures.

While we have described more or less precisely the details of construction, we do not wish to be understood as limiting ourselves 90 thereto, as we contemplate changes in form and the proportion of parts and the substitution of equivalents as circumstances may suggest or render expedient without departing from the spirit of our invention. 95

We claim:

1. In a conveying mechanism, a bucket, a 100 slidably mounted carriage upon which said bucket is adapted to rest, means for imparting a reciprocating movement to said carriage, and means to permit continued movement of said carriage during the period of reversal thereof at one end of its path of travel while said bucket is at rest.

2. In a hoisting mechanism, a carriage, a 105 guideway for said carriage, a bucket arranged to rest upon and be moved by said carriage, reciprocatory means for operating said carriage, and means for supporting said bucket at the lower limit of its travel 110 while said carriage continues its movement, said carriage being adapted to reengage said bucket upon its return movement.

3. In a hoisting mechanism, a carriage, a 115 guideway for said carriage, a bucket permanently connected to and arranged to rest upon said carriage, means for imparting a reciprocating movement to said carriage, and means for supporting said bucket at the lower limit of its travel while said carriage continues its movement and reverses its direction, said carriage being adapted to reengage said bucket upon its return movement.

4. In a hoisting mechanism, a carriage, a 125 vertically extending guideway for said bucket having an angularly disposed part at its upper end, means for imparting a reciprocating movement to said carriage and a corresponding movement to said bucket 130.

carried thereby, said bucket having a part adapted to engage said guideway to cause a tilting thereof by the angular part of said guideway at the upper limit of travel of the 5 bucket, said carriage having a sliding connection with said bucket to permit said tilting, and means to support said bucket in loading position at the lower limit of its travel, said sliding connection and said 10 means for supporting said bucket being adapted to permit continued movement of said carriage and reversal of direction thereof while said bucket is in loading position.

5. In a hoisting mechanism, a bucket, supporting means for carrying said bucket, means for imparting a reciprocating movement to said supporting means, and means for effecting a permanent slidable connection between said supporting means and said 15 bucket to permit continued movement of said supporting means while said bucket is at rest at one limit of its path of travel.

6. In a hoisting mechanism, an elevator, a charging chamber therefor, a pivoted gate 20 controlling the outlet of said chamber, a weight connected to said gate and lying substantially over the pivot thereof when said gate is open and at one side of said pivot when said gate is closed, and a pivoted arm 25 projecting at its opposite ends into the paths of movement of a part carried by said gate and said elevator respectively.

7. In a hoisting mechanism, an elevator, a charging chamber therefor, a pivoted gate 30 controlling the outlet of said chamber, a weight connected to said gate and lying substantially over the pivot thereof when said gate is open and at one side of said pivot when said gate is closed, and a pivoted arm 35 projecting at its opposite ends into the paths of movement of a part carried by said gate and said elevator respectively, said arm projecting into the path of said elevator to such an extent that the movement of the ele- 40

vator only imparts to the gate the first part 45 of its opening movement the remainder thereof being completed by gravity.

8. In a hoisting mechanism, an elevator, a charging chamber therefor, a pivoted gate controlling the outlet of said chamber, a weight connected to said gate and lying substantially over the pivot thereof when said gate is open and at one side of said pivot when said gate is closed, and a pivoted arm 50 projecting at its opposite ends into the paths of movement of a part carried by said gate and said elevator respectively, said arm projecting into the path of said elevator to such an extent that the movement of the elevator only imparts to the gate the first part 55 of its opening movement the remainder thereof being completed by gravity; a part of said gate in its open position overlying said elevator whereby the rising of said elevator starts the closing movement of said door, the remainder of said movement being effected by gravity.

9. In a hoisting mechanism, an elevator, a fixed charging chamber therefor having an inclined bottom and an outlet opening, 70 a pivoted gate for controlling said opening, said gate having a counterbalancing weight carried thereby for normally maintaining the same in closed position, and a pivoted lever having its opposite ends projecting 75 into the paths of movement of said elevator and said gate, respectively, said elevator being adapted to move said lever sufficiently to move said weight above its pivotal axis after which the further opening movement 80 of said gate is effected by gravity.

In testimony whereof, we have subscribed our names.

MARSHALL MILLER.
